UNITED STATES PATENT OFFICE.

FRANK NELSON OLCOTT, OF NEW YORK, N. Y., ASSIGNOR TO BLACK & BOYD MANUFACTURING COMPANY, OF NEW YORK, N. Y., A CORPORATION OF NEW YORK.

DESIGN FOR AN ELECTRIC BRACKET.

43,890.

Specification for Design.

Patented Apr. 22, 1913.

Application filed April 10, 1912. Serial No. 689,910. Term of patent 3½ years.

To all whom it may concern:

Be it known that I, FRANK NELSON OLCOTT, a citizen of the United States, and a resident of the borough of Manhattan, city, county, and State of New York, have invented a new, original, and ornamental Design for an Electric Bracket, (Case C,) of which the following is a specification, reference being had to the accompanying drawing, forming a part thereof.

The drawing represents a front elevation of an electric bracket, showing my new design.

The essential features of the design comprise the plaque-shaped body; with a foliated top and bottom; and the springing arms, of ogee shape, and with ornamental ends, for carrying lamps.

I claim:

The ornamental design for an electric bracket, as shown and described.

FRANK NELSON OLCOTT.
